UNITED STATES PATENT OFFICE.

HARLOW R. BROWN, OF YONKERS, NEW YORK, ASSIGNOR TO PHILIP STROBEL & SONS, INC., OF NEW YORK, N. Y.

DESIGN FOR A TABLE.

46,357.

Specification for Design.

Patented Sept. 8, 1914.

Application filed July 13, 1914. Serial No. 850,832. Term of patent 7 years.

To all whom it may concern:

Be it known that I, HARLOW R. BROWN, a citizen of the United States, residing at Yonkers, county of Westchester, and State of New York, have invented a new, original, and ornamental Design for Tables, of which the following is a specification, reference being had to the accompanying drawing, forming part thereof.

The figure is a perspective view of a table, showing my new design.

I claim:

The ornamental design for a table, as shown.

HARLOW R. BROWN.

Witnesses:

HELEN V. HOLMES,
FREDERICK P. RANDOLPH.
